UNITED STATES PATENT OFFICE.

JAMES SHELLENBARGER ALSPAUGH, OF PORTSMOUTH, OHIO.

MECHANICAL MOVEMENT.

1,308,832.

Specification of Letters Patent.

Patented July 8, 1919.

Application filed September 23, 1918. Serial No. 255,363.

To all whom it may concern:

Be it known that I, JAMES S. ALSPAUGH, a citizen of the United States, residing at Portsmouth, in the county of Scioto and State of Ohio, have invented a new and useful Mechanical Movement, of which the following is a specification.

On February 19, 1918, a patent numbered 1,257,064 was granted to me for sundry improvements in an automatic gear shift control. The structure patented contains a slide mounted for right-line reciprocation, and this present application has for its object, the provision of a simplified means for imparting right-line movement to the slide.

Within the scope of what is claimed, a mechanician may make changes in the device hereinafter described, without departing from the spirit of the invention or placing its utility in jeopardy.

In the drawings:—Figure 1 is a top plan showing the slide at one end of its supporting frame; Fig. 2 is a plan wherein the slide is shown in an intermediate position; Fig. 3 is a plan wherein the slide has been moved to the opposite end of the frame from that shown in Fig. 1; Fig. 4 is a longitudinal section wherein parts are broken away; Fig. 5 is a cross section on the line 5—5 of Fig. 2; Fig. 6 is a fragmental perspective showing a part of the slide; Fig. 7 is a diagram alluded to in explaining the operation of the device.

The numeral 1 marks a frame including end members 2 and superposed bars 5, 4, and 3 separated by spacers 6 and united by securing elements 7. The bar 5 has a rib 8. A slide 9, which is a composite structure, is mounted for right-line reciprocation between the bars 4 and 5, the slide including a plate-like body 10 having a longitudinal web 11 provided with a groove 12 receiving the rib 8, the body 10 having a guideway 16 receiving the bar 3, the slide 9 thus being mounted on the frame 1 for reciprocation in a straight line. The body 10 has a transverse passage 14 adapted to register with a notch 15 in the rib 8 for the reception of a part (not shown) actuated by the slide, the said part constituting no portion of the present improvement over the patented structure hereinbefore mentioned. The body 10 of the slide 9 has notches 17 permitting the slide to have a maximum movement, the notches 55 17 being adapted to receive the spacers 6

which lie between the bars 3 and 4, when the slide is reciprocated.

The body 10 of the slide 9 is supplied with a transverse groove 18 including a wall or abutment 19 disposed at right angles to the outer surface of the body, and a wall 20, opposite to the abutment 19 and slanting longitudinally of the body. The wall 20 and the abutment 19 are located at one end of the groove 18, and at the other end of the groove there is a similar abutment 21 and a slanting wall 22, it being observed, however, that the walls 22 and 20 slant in opposite directions, longitudinally of the body. An inner plate 23 is applied to one edge of the body 10 and has a seat or notch 24 coinciding with the groove 18, the edge of the plate 23 extending as shown at 50 in Fig. 6, beyond the slanting wall 22. An outer plate 25 abuts against the plate 23 and extends across the seat 24. A similar outer plate 28, and an inner plate 26 are disposed at the outer end of that portion of the groove 18 which is formed by the abutment 19 and the slanting wall 20. The numeral 51 denotes the part of the plate 26 which corresponds to the part 50 of the plate 23. The plates 26, 28, 23 and 25 are held on the edges of the body 10 of the slide 9 by means of securing devices 29.

A swinging member 30 is located between the bars 3 and 4 and carries a pivot element 31 received in openings 32 in the bars 3 and 4. The openings 32 are elongated transversely of the bars 3 and 4, and, consequently, the member 30 cannot only swing with the pivot element as a fulcrum, but, as well, may have a slight endwise movement transversely of the bars 3 and 4. There are casings 33 on the member 30, wherein latches 34 and 35 slide, the latches being advanced by compression springs in the casings. The latch 34 co-operates with the slanting wall 22 and the abutment 21, whereas the latch 35 co-operates with the slanting wall 20 and the abutment 19.

The means for actuating the swing member 30 embodies a stud 37 on said member and an actuating rod 38 having a slot 42 located in the rod and in an offset 41 thereon. A retainer is mounted in one end of the rod 38, the retainer being designated by the numeral 39, and there being a compression spring 40 about the rod, the spring engaging the retainer and the adjacent end mem-

ber 2 of the frame 1. The rod 38 is mounted to slide endwise in the portions 2 of the frame.

Let it be supposed that, as shown in Fig. 5 1, the slide 9 is at the left end of the frame 1, the latch 35 resting on the body 10 of the slide under the action of one spring 36, and the latch 34 being projected into the groove 18 under the action of the other 10 spring 36. The rod 38 is drawn to the left, the spring 40 is compressed, the slot 42 in the rod coacts with the stud 37 of the slide 9, and the member 30 swings as shown by the arrows A and B in Fig. 7. The latch 15 34 engages the abutment 21 and moves the slide 9 to the right. The latch 34 enters the seat 24, and because the distance from the inner wall of the seat to the center of the openings 32 is less than the distance 20 from the outer surface of the latch to the center of the pivot element 31, the member 30 will move endwise, the latch 35 being moved outwardly until, as it passes the seat 27, it rides along the edge of the end 25 51 of the plate 26 and along the edge of the plate 28, the latch 35 thus being prevented from engaging the seat 27, and ultimately riding upon the surface of the body 10 of the slide 9. The parts are shown thus 30 in Fig. 3, wherein the slide 9 has been moved to the right at the end of what may be called the first stroke of the member 30. The pin and slot mounting 31—32 for the member 30 permits it to have an endwise 35 movement as above mentioned. Note that the latch 34 has moved out of the seat 24 at the end of the first stroke.

The second stroke of the member 30 is caused by the action of the spring 40, the 40 rod 38 having been released, the member 30 moving in the direction of the arrows C and D of Fig. 7. During the second stroke, the latch 35 rides up the slanting wall 22, upon the surface of the body 10 45 of the slide 9, and the latch 35 enters the groove 18 and coöperates with the abutment 19. Observe the dotted line position of the member 30 in Fig. 3.

On the third stroke, the member 30 moves 50 again in the direction of the arrows A and B, the latch 35 sliding the said member to the left, and the latch 34 riding across the parts 50 and 25, free of the seat 24, as hereinbefore explained in connection with the 55 latch 35, the parts 51 and 28 and the seat

27. During the third stroke, the operator manipulates the rod 38 and compresses the spring 40.

During the fourth stroke, the member 30 swings as indicated by the arrows C and 60 D into the solid line position of Fig. 1, the latch 34 engaging behind the abutment 21, and the latch 35 resting on the part 10, the cycle thus being completed. The fourth 65 stroke is made under the impulse of the spring 40, which was compressed on the third stroke.

I claim:

1. In a device of the class described, a frame; a slide mounted for right-line reciprocation on the frame and provided with a groove having oppositely slanting walls adjacent its ends and supplied with abutments disposed opposite to the slanting walls; a swinging member; latches carried by the swinging member and coöperating with the walls, with the abutments, and with the ends of the groove; and means for mounting said member on the frame pivotally for swinging movement, and for 70 endwise movement when either latch coöperates with the corresponding end of the groove. 75

2. In a device of the class described, a frame; a slide mounted for right-line reciprocation on the frame and provided with a groove having oppositely slanting walls adjacent its ends and supplied with abutments disposed opposite to the slanting walls; a swinging member; latches carried by the swinging member and coöperating with the walls, with the abutments, and with the ends of the groove; means for mounting said member on the frame pivotally for swinging movement, and for endwise movement when either latch coöperates with the corresponding end of the groove; means actuated by an operator for moving the swinging member when one latch engages with the corresponding abutment; 80 and spring means for moving the swinging member to cause either latch to engage with the corresponding abutment. 85

In testimony that I claim the foregoing as my own, I have hereto affixed my signature in the presence of two witnesses.

JAMES SHELLENBARGER ALSPAUGH.
